UNITED STATES PATENT OFFICE

171,449

CHAIN SAW

Harry I. Hazzard, Inglewood, and Vincent C. Tyrrell, Redondo, Calif., assignors to McCulloch Motors Corporation, Los Angeles, Calif., a corporation of Wisconsin

Application March 17, 1953, Serial No. 24,062

Term of patent 14 years

(Cl. D93—3)

To all whom it may concern:

Be it known that we, Harry I. Hazzard, a citizen of the United States, residing at Inglewood, in the county of Los Angeles and State of California, and Vincent C. Tyrrell, a citizen of the United States, residing at Redondo, in the county of Los Angeles and State of California, have invented a new, original, and ornamental Design for a Chain Saw, of which the following is a specification, reference being had to the accompanying drawings, forming a part thereof.

Figure 1 is a side elevational view of a chain saw, showing our new design;

Figure 2 is an elevational view of the opposite side of the saw;

Figure 3 is a plan view;

Figure 4 is an enlarged perspective view of the chain saw.

We claim:

The ornamental design for a chain saw, as shown.

HARRY I. HAZZARD.
VINCENT C. TYRRELL.
